UNITED STATES PATENT OFFICE.

WALLACE PFAU ANDRICK, EDGAR LOWE, AND HOWELL W. HAFF, OF JAMAICA, NEW YORK, ASSIGNEES TO KELLEY MONROE TURNER, OF JAMAICA, NEW YORK.

KEY CONSTRUCTION AND SUPPORT FOR TELEPHONIC APPARATUS.

1,060,576.

Specification of Letters Patent.

Patented May 6, 1913

Application filed March 13, 1911. Serial No. 614,047.

To all whom it may concern:

Be it known that we, WALLACE PFAU ANDRICK, EDGAR LOWE, and HOWELL W. HAFF, citizens of the United States, residing at 5 Jamaica, in the county of Queens and State of New York, have invented a new and useful Improvement in Key Construction and Supports for Telephonic Apparatus, of which the following is a specification.

10 This invention relates to a key construction and support for telephonic apparatus, and particularly to the type of telephone transmitting station set forth in the pending application of Percival G. Burgess, Serial 15 No. 584,414, and in pending application for design patent Serial No. 612,712, filed March 6th, 1911.

The object of the invention is primarily to obtain an escutcheon face key board with 20 keys in a horizontal row or line across the face thereof, and spring blades supported by the same unitary part that constitutes the escutcheon front, this unitary part being formed in such a way as to adapt itself to 25 the purpose of holding the spring blades, supporting the various pivot axes of the keys, serving the purposes of the escutcheon front, accommodating the requisite movement of the keys, properly separating the 30 keys from one another and giving their support adequate rigidity in all directions, and which is compact, ornamental, easily constructed and durable.

With the foregoing in view, the invention 35 consists in the improved key construction and support as hereinafter set forth.

In the drawings, Figure 1, is a side elevation of a key construction and support embodying the principles of our invention; Fig. 40 2, is a similar view showing a depressed position of the key; Fig. 3, is a top plan view; Fig. 4, is a perspective view of the frame; Fig. 5, is a front view showing the key construction and support embodied in an instrument.

The invention will include a unitary frame as 1, which permits requisite movement of the keys and establishes a support therefor, and which further constitutes a support for 50 the spring blades 2.

In the best constructions embodying the invention there will be provided a plate of sheet metal bent into a channel or U shape 55 3, with one side or leg 4 standing vertical and the other side or leg 5 bent into a hori-

zontal plane at a distance considerably below the upper edge of the vertical leg or side. The manner in which the horizontal side or leg is bent is such as to leave an inclined or flattened face 6 along the corner and on the 60 upper side and which may be made more defined by facing off the corner as clearly shown in Fig. 4. Bent as above the plate has a shape adapted to the purposes already mentioned, and in order to give it a high degree 65 of rigidity and serve certain other functions later described there are formed ears 7 projecting upward from the bottom of the channel 3, these ears being of rectangular form so as to fit the channel and extend above 70 the plane of the horizontal ledge 5. As shown in Fig. 3, the ears 7 are punched out of the bottom of the channel 3 and bent upward vertically and parallel with one another.

75 8 denotes lugs or ears formed or bent on the ends of the vertical wall 4 and in alignment with the upper portions of the ears 7.

10 indicates a series of holes drilled through the lugs 8 and ears 7 in alignment, 80 and adapted to receive a fixed spindle 11 constituting a pivot axis or journal support for the various keys 12.

The keys 12 are of the ordinary form having flat side faces and handles 13, and the 85 keys are closely constrained in rectangular openings 14 on the front wall 4, the openings being of such a size as to permit the cylindrical portions 15 of the keys to partly protrude therethrough. 16 denotes limits 90 or stops on the keys which prevent too great a movement in any direction. 17 is a cam roller or rollers supported back of the axis 11. These features are the ordinary construction of keys.

95 The spring blades are also of the ordinary form having contacts 19, an inclined tip 20 for engagement with the cam rollers 17, and an insulating spacing block 21 through which the clamping screws 22 pass downward. The screws are received in the upper flat face of the ledge 5 which constitutes the support for the spring blades and on which all of the groups of spring blades are adapted to be screwed as clearly shown in Fig. 3, 100 so as to coöperate with their respective keys.

105 The wall 4 is adapted to be oxidized or enameled so as to constitute an ornamental escutcheon front for the instrument, as shown in Fig. 5. Also with this object in 110

view a channel 25 may be faced in the front of the wall 4 which has the effect of defining the apparent support for the keys, from the wall or face above. While we have provided this simple means of furnishing the ornamental escutcheon front, we do not desire to entirely limit or restrict ourselves thereto since it is evident that the face 4 may have a separate plate attached thereto for the purposes of ornament instead of being itself oxidized or enameled.

What we claim is:

1. A key construction and support comprising a one piece frame formed of sheet metal having a vertical front wall and a horizontal rear ledge joined by a channel form, keys supported behind and protruding through said wall and projecting downward partly into said channel, and groups of spring blades screwed to the upper surface of said ledge and coöperating with the respective keys.

2. A key construction and support comprising a one piece frame of channel form

having a vertical front wall and a rearwardly extending ledge and having ears bent up from the bottom of the channel and lugs bent over from the ends of said front wall, a spindle passed through said ears and lugs behind said wall, keys supported by said spindle and protruding through said wall and extending down into said channel below said ledge, and groups of spring blades supported by said ledge and adapted to be engaged by said keys, said front wall constituting an escutcheon front, substantially as described.

In testimony whereof, we have signed our names to this specification in the presence of two subscribing witnesses, this seventh day of March, 1911.

WALLACE PFAU ANDRICK.

EDGAR LOWE.

HOWELL W. HAFF.
